(57) **CLAIM**

We claim the ornamental design for a bottle, as shown and described.

DESCRIPTION

FIG. 1 is a top and front perspective view of a bottle;
FIG. 2 is a top and rear perspective view thereof;
FIG. 3 is a front elevational view thereof;
FIG. 4 is a rear elevational view thereof;
FIG. 5 is a bottom plan view thereof;
FIG. 6 is a top plan view thereof;
FIG. 7 is a left side elevational view thereof;
FIG. 8 is a right side elevational view thereof;
FIG. 9 is a cross-sectional view of the bottle taken along
section line 9-9 of FIG. 3; and,
FIG. 10 is an enlarged cross-sectional view of the bottle
taken along section line 10-10 of FIG. 3.
The shade lines in the Figures show contour and not surface
ornamentation. The article of this design is transparent
entirely.
